UNITED STATES PATENT OFFICE.

JOHN RECKTENWALD, OF VENEDY, ILLINOIS, ASSIGNOR OF ONE-SIXTH TO WILLIAM MEYER, ONE-SIXTH TO WILLIAM F. SEGELHORST, AND ONE-SIXTH TO WILLIAM C. STEINMAN, ALL OF VENEDY, ILLINOIS.

ELECTRIC SIGNALING SYSTEM.

1,382,121.

Specification of Letters Patent. Patented June 21, 1921.

Application filed December 22, 1920. Serial No. 432,469.

To all whom it may concern:

Be it known that I, JOHN RECKTENWALD, a citizen of the United States, residing at Venedy, in the county of Washington and State of Illinois, have invented certain new and useful Improvements in Electric Signaling Systems, of which the following is a specification, reference being had to the accompanying drawings.

10 This invention relates to electric signaling systems and has relation more particularly to a device of this general character especially designed and adapted for use in connection with railways, and it is an object of 15 the invention to provide a novel and improved apparatus of this character wherein a warning may be given at a road crossing or other location of the approach of a train and wherein the train is provided with 20 means to indicate that the system is functioning.

Another object of the invention is to provide a novel and improved electric signaling system of this general character wherein 25 the source of electrical energy is carried by the train and more particularly by the locomotive.

It is also an object of the invention to provide a novel and improved system of this 30 general character of an intermittent electrical contact type which is intended to operate a signal carried by a train or locomotive in case of danger ahead and to operate signals at predetermined points along the trackway 35 as a warning that a train is approaching.

The invention consists in the details of construction and in the combination and arrangement of the several parts of my improved electric signaling system whereby

40 certain important advantages are attained and the device rendered simpler, less expensive and otherwise more convenient and advantageous for use, as will be hereinafter more fully set forth.

45 The novel features of my invention will hereinafter be definitely claimed.

In order that my invention may be the better understood, I will now proceed to describe the same with reference to the accompanying drawings, wherein:

Figure 1 is a diagrammatic view partly in rear elevation and partly in section illustrating certain features of my improved electric signaling system as herein disclosed.

Fig. 2 is an enlarged fragmentary view 55 illustrating the means whereby the circuits are controlled by the reversing lever.

Fig. 3 is a view partly in vertical section and partly in elevation of the structure as disclosed in Fig. 2.

Fig. 4 is a view in top plan of the contact members disclosed in Figs. 2 and 3 and a sectional view through the reversing lever illustrating in detail the contact member or button carried by said lever.

Fig. 5 is an enlarged fragmentary sectional view illustrating the mounting of one of the plates to the rail of a trackway.

Fig. 6 is a view in perspective of one of the plates as illustrated in Fig. 5, unapplied.

Fig. 7 is a diagrammatic view in plan of the features of my improved system which are arranged adjacent the trackway.

Fig. 8 is a diagrammatic view in elevation illustrating the initial closing of a circuit, and

Fig. 9 is a view similar to Fig. 8 illustrating a second position of the parts and whereby a circuit is closed to operate the highway signals only.

As disclosed in the accompanying drawings, C denotes a cab of a locomotive of any desired type and wherein is arranged a reversing lever 1 for the throttle valve or other mechanism for controlling the motive force. In the present embodiment of my invention, the lever 1 is supported for swinging movement and at a desired point intermediate its length has disposed therethrough a button or member 2 of electrical conduct- 90 ing material. This button or member 2 is insulated from the lever 1 by a bushing or sleeve 3.

In advance of the lever 1 is a pair of arcuate contact members 4 and a similar pair 95 of contact members 5 is arranged rearwardly of the lever 1. The members 4 and 5 are disposed on a curvature substantially concentric to the fulcrum of the lever 1 so that upon movement of the lever in a forward direction, the button or member 2 will pass between and engage the contact members 4 to close a circuit therethrough. This button or member 2 also, upon rearward movement of the lever 1, passes between and engages 100 the contacts 5 to close a circuit therethrough.

One of the contact members 4 is in electrical connection, as at a, with a dynamo D

or other source of electrical energy through the wire or conductor 6. The adjacent contact member 5 is in electrical connection, as at *b*, with said dynamo D through the wire 5 or conductor 7.

Leading from the connection *b* with the dynamo D to a connection *c* of a bell or other audible signal B is a wire or conductor 8. Each of the remaining contact 10 members 4 and 5 is in electrical connection with a wire or conductor 9 leading to a binding post 10 to be hereinafter more particularly referred to.

Leading from the second connection *d* of 15 the bell or signal B is a wire or conductor 11 which is in electrical connection with a side frame S to be later described.

B' denotes a second bell or audible signal arranged within the cab C and leading from 20 the connection *c'* of said bell *B'* to the connection *a* of the dynamo D is a wire or conductor 8'. A wire or conductor 11' leads from the connection *b'* of the bell *B'* to a second side frame *S'*. It is to be understood 25 that the frames S and *S'* are positioned at opposite sides of the locomotive and substantially directly above the rails R comprised in the trackway over which the locomotive travels.

30 A wire or conductor 12 leads from the connection *c* of the bell or signal B to a plate 13 arranged within the cab C and extending inwardly thereof. A similar wire or conductor 12' leads from the connection 35 *c'* of the bell or signal *B'* to a second plate 13'.

Depending from the locomotive, and more particularly the cab C thereof, is a frame F substantially in the form of an inverted U and of conductive material. The central or intermediate portion 14 of the frame F is secured to the locomotive through the medium of the bolts 15 or otherwise as may best comply with the requirements of practice. The post 10, hereinbefore referred to, is in electrical connection with the frame F or more particularly the intermediate portion 14 thereof. It is also to be understood that the frame F is suitably insulated from 45 the locomotive or more particularly the floor or adjacent wall of the cab C.

The arms 16 of the frame F are vertically disposed and substantially in parallelism and the lower or free end portions of said 50 arms 16 rotatably support and are connected by the axle or spindle 17 of conductive material. Mounted on each end portion of the axle or spindle 17 is a wheel 18 of conductive material which rides upon a 60 rail R.

The side frame S is secured to and supported by one of the side arms 16 of the frame F while the second side frame *S'* is secured to and supported by the second arm 65 16. Each of the side frames S and *S'* is

of electrical conductive material and comprises a vertically disposed portion or member 19 terminating at its opposite ends in the inwardly disposed extensions or arms 20. The extensions or arms 20 terminate 70 in the inwardly disposed feet 21. Each of the feet 21 is secured to the adjacent side arm 16 of the frame F by a bolt or screw 22 or the like. The feet 21, and consequently the side frame, are insulated from 75 the coating arm 16 of the frame F by the washers 23 of non-conductive material, so that any current which may pass through a side frame S or *S'* will not be transmitted through the frame F and vice versa. 80

Slidably disposed through the inwardly directed arms or extensions 20 of each of the side frames S and *S'* is a vertically disposed rod or member 24 of conductive material. The upper end portion of this member extends within the cab C and is adapted to be moved into or out of contact with the adjacent plate 13 or 13' positioned thereabove. 85

Directed transversely through the rod or member 24 at a point within side frame S or *S'* is a pin 25 affording an abutment for one end portion of an expandable spring 26 encircling said member or rod 24 with the opposite end portion bearing against the 90 inner face of the upper arm or extension 20. By this means, the rod or member 24 is constantly urged downwardly so that normally the upper end portion of said member or rod 24 is out of contact with plate 13 or 13'. The pin 25, hereinbefore referred to, also contacts with the upper face of the lower arm or extension 20 of side frame S or *S'* to limit the downward movement of the member or rod 24 under the influence 100 of the spring 26.

The lower end portion of each of the members or rods 24 is provided with a wheel 27 in electrical contact therewith and which wheel is adapted to contact with the plates P carried by the rails R at predetermined spaced points therealong and arranged outwardly of said rails. Each of the plates P is 110 comprised of a central or intermediate straight portion 28 of desired length terminating at 115 opposite ends in the downwardly and outwardly inclined portions 29.

The central or intermediate straight portion 28 of the plate P is of a width greater than the width of each of the inclined end 120 portions 29, with said portions 29 in continuity with the outer marginal portions of the intermediate or central portion 28. The inner margin of the central or intermediate portion 28 of the plate P is defined by a 125 depending flange 30. This flange 30 is adapted to be clamped, as at 31, to a fish plate 32. The plate 32 is held in operative engagement with a rail R through the medium of a clamping member 33. 130

The trackway is divided, as at *x* into blocks and in the present embodiment of my invention a block is shown to be of a length extending from one highway *H* to another, 5 although I do not wish to be understood as limiting myself to this particular or exact arrangement. It is also to be understood that the rail sections of one of the blocks are insulated in a conventional manner from 10 the rail sections of the adjacent blocks. Adjacent each highway *H* and to one side of the trackway is a support 34 herein disclosed as a post and mounted upon said support is an electric bell 35 or other audible signal and 15 an electric light 36 or other visual signal, said bell 35 and light 36 being herein disclosed as electrically connected in series by the wires or conductors 37, although it is to be understood that the same may be otherwise 20 electrically connected as may best comply with the requirements of practice.

The wires or conductors 38 and 40 lead from one of the connections *f* with the bell 35, one of said wires or conductors as 38 being 25 in electrical connection with one rail in a block of the trackway and the second conductor or wire 40 being electrically connected in series with the plates *P* of the second or adjacent block of the trackway and with 30 the plates carried by the rail of the second block remote from the rail of the first named block with which the wire or conductor 38 is electrically connected.

The wires or conductors 39 and 41 lead 35 from the second connection *e* with the bell 35, one of said wires or conductors as 39 being electrically connected in series with the plates *P* carried by the rail *R* of the first block with which the wire or conductor 38 40 is electrically connected. The wire or conductor 41 is in electrical connection with the rail of the second block of the trackway carrying the plates *P* with which the wire or conductor 40 is electrically connected in series. 45

When the lever 1 is moved forwardly, the member or button 2 bridges or connects the contact members 4 so that an electric current may flow from the dynamo *D* through the 50 wire 8 to the bell *B* and from the bell *B* through the wire 11 to an outside frame *S*. From the frame *S*, the current is adapted to flow through the elongated rod or member 24 and the coacting wheel 27. When the 55 wheel 27 contacts with an end or inclined portion 29 of a plate, the circuit is continued through said plate and through a wire or conductor 40 to the bell 35 and light 36 in advance of the train. The current then continues 60 through the wire 41 to a rail *R* and up through the wheel 18 and frame *F* and through the wire or conductor 9 back to one of the contacts 4.

When a wheel 27 is in contact with the 65 end portions 29 of a plate, the highway sig-

nals 35 and 36 and the cab signal or bell *B* are in electrical connection with the dynamo *D*, the ringing of the bell *B* in the cab serving to notify the engine man that the apparatus or system is properly functioning. As 70 the wheel 27 rides up on an inclined end portion 29 of a plate *P*, the elongated member or rod 24 is raised so that when the wheel 27 is passing over the intermediate or central straight portion 28 of the plate *P*, 75 the upper end portion of the member or rod 24 contacts with a plate 13. This results in the bell *B* being cut out as the circuit then runs through the wire or conductor 12, through the member or rod 24, the wheel 27, 80 plate *P*, and from the plate *P* through wire 40 to the highway signals 35 and 36, and thence through wire 41 to a rail *R*. From the rail *R*, the current passes up by way of wheel 18 through the frame *F* to the wire or conductor 9. The system operates, as hereinbefore stated, with the same advantage when the lever 1 is pushed rearwardly, in which event the operating circuit is closed through the contact members 5. 90

In the event any one of the wires or conductors, a rail *R*, or a plate *P* becomes broken, the bell *B* in the cab will not ring. This will clearly indicate to the engine man that he must proceed with caution. 95

When a train is traveling in the direction of the arrow, as indicated in Fig. 7, the shoe or wheel 27 on the right hand side of the train contacts with the inclined portions or ramps 29 of the plates *P* at the right side 100 of the trackway and when the contacts 4 are bridged, the circuit, traced in reverse order, is from the connection *a* with the dynamo *D*, through conductor 6, the contacts 4, conductor 9, frame *F*, the rail *R*, 105 conductor 41, through bell 35, conductor 40, plate *P*, wheel or shoe 27, frame 19, conductor 11, bell *B*, through conductor 8, to connection *b* with the dynamo *D*. When the train is traveling in the opposite direction, 110 the contacts 5 are bridged, the circuit is closed from the contact *b*, through the conductor 7, the contacts 5, conductor 9, through the frame *F*, through the rail at the left of the track, through the conductor 38, through 115 the bell 35, the conductor 39, to a plate carried by the left rail of the trackway, through the left shoe or wheel 27, frame *S'*, the conductor 11', bell *B'*, to the connection *a* with the dynamo *D*. 120

From the foregoing description it is thought to be obvious that an electric signaling system constructed in accordance with my invention is particularly well adapted for use by reason of the convenience and facility with which it may be assembled and operated, and it will also be obvious that my invention is susceptible of some change and modification without departing from the principles and spirit thereof and 125 130

for this reason I do not wish to be understood as limiting myself to the precise arrangement and formation of the several parts herein shown in carrying out my invention in practice except as hereinafter claimed.

I claim:

1. An electric signaling system comprising, in combination, a trackway, a highway signal, contact members carried by a rail of the trackway, said highway signal being in electrical connection with the contact members and a rail of the trackway, rolling stock traveling on the trackway, a source of electrical energy carried by said rolling stock, a shoe carried by the rolling stock for contact with the contact members, said shoe being movable in a vertical direction toward or from each of the contact members, means for constantly urging the shoe downwardly, an electrical connection between the shoe and the source of electrical energy, a member carried by the rolling stock and contacting with a rail, means for electrically connecting said last named member with the source of electrical energy, a contact member carried by the rolling stock, a normally open shunt circuit connecting the second named contact member and the electrical connection between the shoe and the source of electrical energy, a signal carried by the rolling stock and interposed in the first named electrical connection, and coating means carried by the shoe and each of the first named contact members for closing the shunt circuit through the last named contact member and thereby cutting out the last named signal.
2. An electric signaling system comprising, in combination, a trackway, a highway signal, contact members carried by a rail of the trackway, said highway signal being in electrical connection with the contact members and with a rail of the trackway, rolling stock adapted to travel on the trackway, a source of electrical energy carried by said rolling stock, a shoe carried by the rolling stock for engagement with the contact members of the rail, said shoe being supported by the rolling stock for movement in a vertical direction, means for constantly urging the shoe downwardly, the end portions of the contact members being inclined downwardly whereby the shoe moves upwardly and downwardly as the same passes over and contacts with each of the contact members, an electrical connection between the shoe and the source of electrical energy, a member having electrical connection with the rail of the trackway with which the highway signal is electrically connected, an electrical connection with said member and the source of electrical energy, a normally open shunt circuit associated with the electrical connections between the shoe and the member, and a signal interposed in the first named electrical connection, said shunt circuit being closed when the shoe is moved upwardly by contact with a contact member and being open when the shoe is riding over and contacting with the inclined portions of the contact members.

In testimony whereof I hereunto affix my signature.

JOHN RECKTENWALD.
